(57) **CLAIM**

The ornamental design for a speaker assembly, as shown and described.

DESCRIPTION

FIG. 1 is a top, front and right side perspective view of embodiment one, of a speaker assembly, showing our new design;

FIG. 2 is a top, rear and right side perspective view of the speaker assembly of FIG. 1;

FIG. 3 is front elevation view of the speaker assembly of FIG. 1;

FIG. 4 is a top plan view of the speaker assembly of FIG. 1; FIG. 5 is a right side elevation view of the speaker assembly of FIG. 1, wherein a left side elevation view of the speaker assembly is a mirror image thereof;

FIG. 6 is a rear elevation view of the speaker assembly of FIG. 1;

FIG. 7 is a bottom plan view of the speaker assembly of FIG. 1;

FIG. 8 is a bottom, rear and right side perspective view of the speaker assembly of FIG. 1;

FIG. 9 is a top, front and right side perspective view of embodiment two, of a speaker assembly, showing our new design;

FIG. 10 is a top, rear and right side perspective view of the speaker assembly of FIG. 9;

FIG. 11 is front elevation view of the speaker assembly of FIG. 9;

FIG. 12 is a top plan view of the speaker assembly of FIG. 9;

FIG. 13 is a right side elevation view of the speaker assembly of FIG. 9, wherein a left side elevation view of the speaker assembly is a mirror image thereof;

FIG. 14 is a rear elevation view of the speaker assembly of FIG. 9;

FIG. 15 is a bottom plan view of the speaker assembly of FIG. 9;

FIG. 16 is a bottom, rear and right side perspective view of the speaker assembly of FIG. 9;

(Continued)

FIG. 17 is a top, front and right side perspective view of embodiment three, of a speaker assembly, showing our new design;
FIG. 18 is a top, rear and right side perspective view of the speaker assembly of FIG. 17;
FIG. 19 is front elevation view of the speaker assembly of FIG. 17;
FIG. 20 is a top plan view of the speaker assembly of FIG. 17;
FIG. 21 is a right side elevation view of the speaker assembly of FIG. 17, wherein a left side elevation view of the speaker assembly is a mirror image thereof;
FIG. 22 is a rear elevation view of the speaker assembly of FIG. 17;
FIG. 23 is a bottom plan view of the speaker assembly of FIG. 17;
FIG. 24 is a bottom, rear and right side perspective view of the speaker assembly of FIG. 17;
FIG. 25 is a top, front and right side perspective view of embodiment four, of a speaker assembly, showing our new design;
FIG. 26 is a top, rear and right side perspective view of the speaker assembly of FIG. 25;
FIG. 27 is front elevation view of the speaker assembly of FIG. 25;
FIG. 28 is a top plan view of the speaker assembly of FIG. 25;
FIG. 29 is a right side elevation view of the speaker assembly of FIG. 25, wherein a left side elevation view of the speaker assembly is a mirror image thereof;
FIG. 30 is a rear elevation view of the speaker assembly of FIG. 25;
FIG. 31 is a bottom plan view of the speaker assembly of FIG. 25; and,

FIG. 32 is a bottom, rear and right side perspective view of the speaker assembly of FIG. 25.
The broken lines in the figures illustrate portions of the design that form no part of the claimed design.
